FLOOR FURNACE

Harry C. Little, San Rafael, Calif.

Application August 29, 1938, Serial No. 227,373

3 Claims. (Cl. 126—116)

The invention relates to air circulating heaters and more particularly to that type of heater commonly referred to as a floor furnace.

An object of the present invention is to provide a floor furnace of the character described utilizing an oil burner wherein all the means of control for the burner are brought to the top of the unit and made readily accessible at the floor level of the furnace.

10 Another object of the invention is to provide a floor furnace of the character above having an improved igniting means and an improved control of oil flow to the burner for rendering the furnace easier and safer to use than similar types 15 of construction heretofore.

15 A further object of the invention is to provide a floor furnace of the character described having a compact and efficient arrangement of parts and air passages to circulate an abundant quantity of heated air and wherein the air circulated 20 is drawn from the coldest strata within the room being heated, that is, adjacent the floor.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawing and description 30 may be adopted within the scope of the invention as set forth in the claims.

Referring to said drawing:

Figure 1 is a vertical sectional view of a floor 35 furnace constructed in accordance with the present invention.

Figure 2 is a horizontal sectional view of the furnace taken substantially on the plane of line 2—2 of Figure 1.

40 Figure 3 is a fragmentary vertical sectional view of part of the top grill and ignition member.

Figure 4 is a fragmentary vertical sectional view of a part of the top grill and a safety control member.

45 Figure 5 is a fragmentary vertical sectional view of part of the top grill and a portion of the oil flow control member.

Figure 6 is a vertical sectional view of an oil flow control unit used in the present furnace.

50 The floor furnace of the present invention and as illustrated in the accompanying drawing consists briefly of a plurality of inner and outer casings providing a combustion or heater chamber and surrounding air passages for circulating air in thermal contact with the heater casing, an

oil burner mounted under and adapted to heat the heater casing, means for automatically and manually controlling the oil flow to the oil burner and a plurality of controls therefor arranged and constructed in a manner making the same 5 accessible at the top of the unit, the whole being designed and constructed as a single integrally formed heating plant ready for immediate installation in a suitably formed opening in a floor or the like.

With the reference more particularly to the accompanying drawing, the unit comprises an inner centrally disposed, closed top, casing 11 which provides a combustion chamber for an oil burner 12 mounted directly under the bottom wall 13 10 of the casing 11, and which is provided with a burner throat 14 extended through an opening 16 in the bottom wall 13 to discharge the heated burning products from the burner into the combustion chamber. The casing 11 is provided with 15 a discharge outlet conduit 17 extending laterally from adjacent the bottom thereof for conveying the spent products to a flue. The oil burner here used consists of an elongated carburetor casing 18 formed with the discharge throat 14 and one 20 end thereof extending laterally therefrom to provide a carburation or hydroxylation chamber for oil vaporized within the casing and "primary" air admitted to the casing. Oil or other liquid fuel is introduced into the casing 18 from an end 25 19 opposite to the burner throat 14, and in the form of the burner here illustrated, the liquid fuel gravitates over the bottom of the burner towards the discharge throat and in so moving 30 vaporizes and is mixed with a quantity of air 35 admitted through suitable openings in the casing, and the oil vapor and air mixture is discharged through the throat 14 where the mixture is engaged by a supply of "secondary" air 40 to support combustion either in or above the 45 throat.

To provide a most efficient circulation of air around and in thermal contact with the casing 11 I enclose this casing within an outer casing 21 to provide between the casings confined air 45 channels wherein the air is held in thermal contact with the heater casing and caused to rapidly rise through the furnace and into the room. Preferably a majority of the air circulated through the furnace is withdrawn from the room 50 being heated and to effect this result, I provide between the casings 11 and 21 an intermediate vertical wall 22 which divides the air space between the inner and outer casings into a pair of vertical air passages 23 and 24. As a result of 55

this construction the air in the passage 24 adjacent the heater casing 11 is caused to rise and produce a reduced pressure at the bottom thereof which is communicated with the bottom of 5 the passage 23 to thereby cause a downward flow of air in the passage 22. By communicating the upper ends of both of the passages into the room, air will be withdrawn from the room into the passage 23 and discharged back into the room 10 from the furnace by way of passage 24. Mounted over the casings 11 and 21 and secured to the latter casing and the intermediate wall 22 is a perforate plate or grill 26 which is adapted for mounting in a suitably formed opening in a 15 floor or the like. The grill 26 as here shown is formed of a plurality of rectangularly extending grill elements 27 which provide for the free circulation of air therethrough into and from the air passages of the furnace. As here shown, the 20 top 28 of the inner casing 11 is spaced well below the grill 26 so as to define an air space 29 therebetween which is communicated with the upper ends of the inner passage 24. This construction is desirable in order to maintain the grill at a 25 relatively low and safe temperature by minimizing the direct radiation of heat from the heater casing to the grill and by circulating a large quantity of air through the grill.

As an important feature of the present furnace 30 I provide an improved means for igniting the oil or other fuel in the burner casing which is designed to safely and conveniently and positively effect ignition of the fuel. As here shown, this means is embodied in the form of an elongated 35 igniting rod 31 which is mounted through an opening 32 provided in the top 28 of the casing 11 and extends vertically through the interior of the casing and the burner throat to position the lower end 33 of the rod within the burner 40 casing adjacent the bottom thereof. The upper end 34 of the rod is extended above the top wall 28 of the casing to immediately under the grill 26 and the latter is provided with a small removable section 36 directly over the upper end 34 of the 45 rod for removal of the rod through the grill. The rod end 34 may as here shown be provided with a looped portion for ready manual engagement. Any suitable ignition means may be provided at the lower end of the rod and as here shown, such 50 means is embodied in the form of a wick 37 which is removable with the rod for igniting outside of the unit and for replacement in burning form into the burner casing for igniting the oil therein. Preferably means is used to close the opening 32 in order to seal off the products of combustion in the casing 11, and as here shown, such means is embodied in the form of a closure 38 mounted on the rod for engagement with the side walls of the opening. Preferably, to 55 improve the seal of the closure in the opening, the periphery of the closure and the side wall of the opening are tapered downwardly so as to provide a wedged engagement between the closure and the sides of the opening. In the present construction, the closure is in the form of a conical plug which is slidably mounted on the rod 31 so as to allow for expansion and contraction of the rod without raising the closure from its seated 60 position in the opening, and also to retain the member in the opening until the lower end of the rod is brought up to the closure. If desired the downward movement of the rod through the closure may be limited, as by a collar 39 here 65 shown, so as to normally space the lower end of

the rod slightly above the bottom of the burner casing.

The oil flow control means of the present construction is of an automatic and manual control type and is so arranged that the operating controls therefor may be positioned at the upper end of the unit as aforementioned for ready adjustment at the floor level of the room. As here shown, the control means is embodied in a valve casing 39 having oil inlet and discharge passages 41 and 42 which communicate with an interior chamber 45 of the casing. The discharge passage 42 of the casing is connected by means of a conduit 43 with an oil inlet fitting 44 at the end 49 of the burner casing. Mounted in a portion 46 of the discharge passage 42 is a manually controlled valve 47 for controlling the flow of oil to the burner and as will be seen from Figure 6, the valve consists of a vertically mounted tubular member 48 having side openings 49 opening into the chamber and a slot 51 at its lower end which cooperates with such end and an adjacent end and slotted portion in the passage portion 46 to regulate the oil flow in accordance with the rotated and longitudinal position of the valve member. In the present unit this member is extended vertically through the cover 52 of the casing and is supported on a circumferentially inclined surface 53 in the cover for causing a longitudinal displacement of the valve member incident to 30 a rotational displacement thereof. A control member 54 extending vertically from the valve casing is secured at its lower end 56 to the upper end of the valve member and is journaled at its upper end 60 in a socket 57 provided in the grill. As here shown, the end 60 of the member 54 is 35 preferably formed of a non-circular cross section for engagement in and turning by a key 58 which may be inserted into the socket 57 about the member end 56.

Also embodied in the valve casing is an automatic means for maintaining a constant oil level in the casing during discharge of oil to the burner. This means as here shown consists of a valve 59 mounted in a portion 61 of the inlet passage 41 and which is automatically opened and closed by means of a float 62 within the casing. The valve 59 is thus automatically opened and closed in accordance with the opening and closing of the discharge valve to maintain a constant oil level in the casing. Preferably, however, means is provided for manually controlling the valve 59 and also for automatically closing the valve upon an undesired accumulation of oil in the casing. In the present form of the control 40 unit the upper end of valve 59 is mounted under a lever 63 which is pivoted adjacent one end 64 of the casing and extends transversely across to adjacent an opposite end 66 of the casing, where the same is extended through a vertical slot 67 45 to the exterior of the casing, thereby exposing an end portion 68 of the lever at the exterior of the casing for manual vertical adjustment in the slot. The lever is normally held depressed against the valve 59 to hold the same in closed 50 position by means of a spring 69 mounted between the end wall 66 and a part 71 of the lever. The lever may, however, be held in raised position, thereby releasing the valve 59 for automatic 55 operation by the float, by means of a catch or dog 72 provided on a second lever 73 and engaging under a lug 74 on the lever 63. The lever 73 is pivoted to a transversely extending pin 76 adjacent the end 66 of the casing and adjacent the dog 72 provided on the lever and one end 77 of

the lever is secured to a second float 78 mounted in an auxiliary vertical cylinder 79 in the casing. Should the discharge valve become clogged or the oil start to accumulate in the casing, the oil upon reaching the upper end 81 of the cylinder, will pass into the cylinder and raise the float 78 to thereby rock the lever 73 and withdraw the dog 72 from the lug 74 and release the lever 63 for movement under the influence of spring 69 to close the discharge valve 59. The opposite end 82 of the lever 73 is extended from the side wall 66 through the slot 67 directly over the end 68 of the lever 63 for manual rocking of the lever to release the lever 63. As here shown, the catch 15 72 is so curved as to cause an automatic rocking of lever 73 upon raising of lever 63 to engage the lug thereon with the catch so that the lever 63 is set in upper position merely by raising the same to properly engage the catch.

20 In starting of the burner it is necessary to raise the lever 63 in order to open the inlet passage to the casing and allow the valve 59 to be automatically controlled to maintain a constant oil level in the casing for discharge into the burner. On the other hand, when the oil flow is to be shut off to the burner, it is desirable to close both the inlet and discharge valves in the valve casing so as to insure a stopping of the oil flow. Accordingly, I provide means for manually 25 30 35 40 45 50 55 60 65 70 75 80 85 90 95 100 105 110 115 120 125 130 135 140 145 150 155 160 165 170 175 180 185 190 195 200 205 210 215 220 225 230 235 adapted upon vertical movement to close or permit opening of said inlet valve by said float and positioned below the floor level comprising, a rod, means for supporting said rod in vertical position 5 extending from adjacent said valve mechanism to adjacent the floor level, the lower end of said rod being formed with a slot adapted to extend

over said levers and having closed ends spaced over and under said upper and lower levers respectively and adapted upon vertical reciprocation of said rod to engage and depress said upper lever and engage and raise said lower lever. 5

HARRY C. LITTLE.
